PILE FABRIC

Walter A. Rice and Frank G. Shinn, Yonkers,
N. Y.

Application March 26, 1932, Serial No. 601,420

19 Claims. (Cl. 139—400)

Our invention relates to knotted fabrics with knots of the general character of Persian or Sehna rugs, but which contain warp threads of two distinct types, (1) those corresponding in general with normal chain warp threads in that they have normal warp thread tension and are woven in with the weft threads but also carry tufts, called herein chain warps, and (2) other warp threads comparable with stuffer or filler warp threads in their character and in the extra tension put upon them by entering into the weave to the extent that knots are formed about some of them. These of the second type improve the body, assist in retaining accurate width throughout and reduce tendency to pucker and are called herein stuffer type or filler type warps.

A purpose of our invention is to introduce stuffer warps in a tufted or knotted fabric parallel with the chain warps in such manner as to reduce tendency to pucker in the finished fabric, and to cover the stuffer type warps at the back by the tufts or knots.

A further purpose is to introduce weft threads in combination with stuffer warps in a tufted or knotted fabric having the tufts or knots surrounding the warps so as to prevent narrowing of the fabric during weaving.

In a fabric containing stuffer or filler type warps a further purpose is to produce a Persian or Sehna knot weave having all of the yarn tufts in one course formed as right hand knots, and all of the yarn tufts in the next course formed as left hand knots, adjoining courses alternating right and left hand throughout the weave.

In a fabric containing stuffer or filler warps, a further purpose is to produce a Persian or Sehna knot weave having the yarn tufts in adjoining courses formed about pairs or sets of warps which differ in the pairing or arrangement of the warps.

In a fabric containing stuffer type or filler type warps, a further purpose is to produce a Persian or Sehna knot weave having the yarn tufts in adjoining courses formed about pairs or sets of warps which differ in the pairing or arrangement of the warps, and the knots alternating, right and left hand in adjoining courses.

A further purpose is to bind Persian or Sehna knots upon chain and stuffer type or filler type warps arranged in trios of two chain warps and one stuffer type warp, the stuffer type warp having any given position or relation with respect to the chain warps, and using wefts of a single shot of yarn.

A further purpose is to bind Persian or Sehna knots upon chain and stuffer type or filler type

warps arranged in trios of two chain warps and one stuffer type warp, the stuffer type warp having any given position or relation with respect to the chain warps, by wefts of a double shot and which are carried together both over and under any selected prearrangement of stuffer type and chain warps.

A further purpose is to introduce stuffer type warps in a tufted fabric while maintaining a clear design on the back of the fabric.

A further purpose is to introduce stuffer type warps into a tufted fabric and at the same time cover up the stuffer type warps so that they shall not show objectionably through from the back of the fabric.

A further purpose is to cover stuffer type warp threads in a fabric by pile yarn so that the stuffer type warp threads will not show sufficiently at the back of the fabric to interfere with the symmetry of the design.

A further purpose is to provide various alternative available combinations of stuffer type and chain warp threads and knots in a tufted fabric.

A further purpose is to form combinations of different or differently placed tuft knots without interfering with the advantages secured from stuffer type warp thread use.

A further purpose is to include stuffer warp threads along with chain warp threads within the knots or loops of a pile fabric covering the stuffer warp threads within the knots by the pile yarn.

Further purposes will appear in the specification and in the claims.

Our invention comprehends not only the methods or processes involved, but fabrics produced by the methods or processes.

Without the least attempt to show all of the forms in which our invention may appear, we present a considerable number of illustrative constructions for the purpose of showing the breadth of the invention and its applicability to conditions variant not only in the number of chain and filler type warp threads to the same cycle, but in the position of the filler warp threads with respect to the chain warp threads, in the position of the knots, the number of warp threads included within each knot, in the grouping of the warp threads for a knot engagement, whether the same be in successive rows or different in successive rows, and the placing of the knots whether right-facing or left-facing in the rows of alternating in adjoining rows.

We have also shown variant wefts in some of

the different structures to indicate the novelty of some of the combinations shown.

Figure 1 is a perspective elevation of the face of one form of our improved fabric, showing the 5 warp threads, wefts and tuft loops, all separated or extended as though loosely woven, and their size magnified.

Figure 2 is a sectional elevation of the fabric shown in Figure 1 parallel with the lengths of 10 the warp threads.

Figures 3, 5, 7, 32, 34, 36 and 38 are views graphically similar to Figure 1 but showing variations of knot formation or location.

Figures 4, 6, 8, 33, 35, 37 and 39 are sectional 15 elevations of Figures 3, 5, 7, 32, 34, 36 and 38 respectively, taken parallel with the lengths of the warp threads.

Figure 8a is a slight modification of Figure 8.

Figures 9 to 26 are enlarged sections of knot 20 formations, not intended to be a complete showing of the possible knots but sufficiently complete to illustrate that wide variation is available in the arrangement of warps and formations of knots. Some of the knots are formed right hand 25 and some left hand.

Figures 27a, 27b, 27c in one group; 28a, 28b, 28c in a second group; 29a, 29b, 29c in a third group; 30a, 30b, 30c in a fourth group and 31a, 31b, 31c in a fifth group are arrangements in 30 each group of a plurality of enlarged sections of knot formations with the immediate weft shown in position and illustrating in each group successive arrangements of adjoining courses.

In Figures 40 and 41 warp threads only are 35 shown to illustrate the fact that in four-warp-thread combinations the stuffer type warp threads can represent the outside threads of the group of 4 or the inside threads of a group of four according to the judgment of the designer 40 in view of the information here given.

Throughout the drawings the stuffer type warps are illustrated in shaded lines, while the chain warps are shown by double lines, as are the wefts and tufts.

45 In the drawings similar numerals indicate like parts.

In the manufacture of knotted rugs it is quite desirable to use stuffer type or filler type warp threads in order to maintain the width and 50 increase the stiffness or body of the rugs. The insertion of stuffer type or filler type warp threads has been objectionable in the past for the reason, among others, that these warps have not been covered sufficiently at the back and that the 55 stuffer type or filler type warp threads have not been fully coordinated with the rest of the rug. The failure to cover sufficiently causes interference with the symmetry of the design. We offer relief from this partially or completely by surrounding the filler type warp threads by some 60 or by all of the knots by which the tufts are made. We very thoroughly bind the stuffer type warp threads into the rug by passing the material of the same knots about the stuffer type warp 65 threads and the chain warp threads so that the filler type warp threads are tied to the rug not only by the normal weaving operation, but by the knots as well.

In the figures the warp threads are arranged 70 in various repeated groups preferably three or four to the group, each group containing at least one stuffer type or filler type warp thread and two chain warp threads.

Within the groups there are as illustrated either 75 two chain warp threads to one stuffer type warp

thread or chain warp threads alternating successively or in pairs with stuffer type warp threads.

For convenience in reference we have given all 5 of the warp threads shown individual reference characters notwithstanding that they repeat successively in groups of three or of four only. In the four-warp-thread group such as in Figures 34-41, the stuffer type warp threads are shown two to each group, at 45, 46, 47, 48, 49, 50, 51 10 and 52. In the three-warp-thread groups, such as Figures 1-8 the stuffer warp threads are shown one to each group at 45, 47, 49, 51 and 53. The chain warp threads are shown in the three-warp-thread groups at 54-63 and in the four-warp-thread groups at 54, 56, 58, 60, 62, 64, 66 and 68. 15

The knots shown are as of eight types or arrangements differing in being rights or lefts, containing one warp thread only within the eye or two warp threads within the eye and/or looping 20 one or two warp threads. Different locations of the stuffer type and chain warp threads within or with respect to the eyes and loops also affect the situation.

The knots are shown separately with the eye 25 enclosing one warp thread only and the loop enclosing one warp thread only, right at 69, Figures 11, 15, 16 and 23 and left at 70, Figures 12, 19, 20 and 26; with the eye enclosing one warp thread only and the loop enclosing two warp 30 threads, right at 71 in Figures 9, 14, 22 and left at 72 in Figures 18 and 25; with the eye enclosing two warp threads and the loop enclosing one warp thread, right at 73 in Figures 10, 13 and 21 and left at 74, in Figures 17 and 24. 35

In Figures 32 to 39 knots are shown enclosing two warp threads in the eye and also two warp threads in the loop, right at 75 and left at 76.

It is recognized that these are all Persian or Sehna knots of recognized type and that the 40 question of right or left formation and of the number of warp threads enclosed within the eye and loop parts of the knot, respectively, will depend upon the location intended for the tuft ends, the proportion and placing of the stuffer 45 type warp inserted and other factors.

It will be apparent that with all of these formations shown, the knots enclosing a total of two warp threads only may be made to enclose (back, that is, cover the back of) a stuffer type 50 warp thread or not as desired; that with a three-warp grouping the knots which enclose three warp threads will always back the stuffer type warps; that with a four-warp formation a knot enclosing three stuffer type warp threads may 55 be made to enclose and back both stuffer type warp threads or one only as preferred; and that with a four-warp thread grouping a knot enclosing four warp threads will necessarily enclose and therefore back and cover all of the warp 60 threads.

With all of the knots indicated as seen above there can be wide variation as to which one or which ones of the warp threads is or are made stuffer type warp threads and which one or ones 65 is or are made chain warp threads. We have gone into this description to the extent above for the purpose of showing the wide flexibility of our invention in applying to all kinds of combinations of chain and stuffer type warp threads 70 in differing relations with combinations of size, proportion of eye to loop, right and left presentation and lateral shifting location of the knots used while still carrying out the coverage feature of our invention either completely to form 75

a backing for all of the stuffer type warp threads or partially to form a coverage for part of the stuffer type warp threads.

The weft threads are shown at 77, 78, 79 and 80.

In Figures 1 and 2 it will be seen that in a three-warp-grouping right handed knots 77 are shown having the eye of the knot about a single chain warp thread and the loop about an adjoining stuffer type warp thread and the other chain warp thread, giving full tuft coverage for the backs of the stuffer type warp threads. Two weft threads 77 and 78 are shown between adjoining rows of tufts the weft threads being separately applied and alternating one over and the other under the same warp threads.

In Figures 3 and 4 groups of three warp threads are shown with the same weft provision as in Figures 1 and 2. However, the knots 20 are of the 73 type, having each eye of a knot encircling a stuffer type warp thread and a chain warp thread and the loop enclosing the second chain warp thread of the set. The knots are all right handed here.

In Figures 5 and 6 right and left hand knots 69 and 70 are shown, the eyes of successive rows of knots encircling the same chain warp threads and the loops of the knots surrounding the adjoining warp threads on opposite sides respectively so that one row of knots covers the backs of the stuffer type warp threads and the other row of knots does not. This gives partial coverage. The weft thread arrangement is the same as in Figures 1 to 4.

In Figures 7 and 8, also a three warp thread grouping having the same character of weft as in Figures 1 to 6, the same character of knot 69 is used for all of the rows as for the right hand knot rows in Figure 5, but the eye of each knot 40 encircles the stuffer type warp thread of this group so that one chain warp thread of each group is not covered. This formation gives knot coverage for all of the stuffer type warp threads except, of course, in the distance between the 45 loops where the two wefts lie in which half of the weft threads lie over and half under the stuffer type warp.

Figure 8a is intended to indicate four weft threads 77, 78, 79 and 80 for each row of tufts or knots, the four weft threads alternating above and below the stuffer type warp threads and between them and the chain warp threads.

In Figure 27 groupings of three are shown with knots 71 and 72 whose eyes each encircle a chain warp thread and whose loops each enclose one stuffer type warp thread and one chain warp thread. This is true notwithstanding that successive rows are rights and lefts respectively so that the chain warp thread enclosed by the eye 60 is different in successive rows or courses.

Any suitable shuttle- or needle-laid weft may be used.

In Figure 28 the knots 24 are all left hand and the successive rows surround different groupings of three warp threads so that the stuffer type warp thread forms the middle of the group in one row and is surrounded by the eye of the knot, but forms an end of its group in the next row and is surrounded by the loop of the knot. 70 Here, as in Figure 27, there is full knot coverage for all of the stuffer type warp threads.

In Figure 29 the knots 71 and 72 are rights and lefts respectively and there is a shift in the grouping of the warp threads in successive 75 rows. By reason of the location of the stuffer

type warp threads as shown in the particular position in the eyes of the knots, they are included within the eyes of the knots in all of the rows but would form full knot coverage in any event.

In Figure 30 right and left knots 69 and 70 are used, each covering a pair of warp threads but shifting the pair, within a three warp thread arrangement in successive rows, with the result that in alternate rows the stuffer type warp 10 threads are not enclosed within the knots and there is only partial knot coverage for the stuffer type warp threads. This is true also of Figure 31 where all of the knots are right hand knots 69 but where the pairs covered by the knots 15 are shifted in alternate rows.

In Figures 32 to 41 all of the groups are four-warp-thread groups and each of the knots encloses two warp threads within each eye and two warp threads within each loop.

The arrangements of the warp threads are the same in Figures 32 to 39, alternating stuffer type warp threads and chain warp threads but in Figures 40 and 41 the stuffer type warp threads are both on the outside of the group in Figure 25 40 and both on the inside of the group in Figure 41. This means that across the rug two stuffer type warp threads will adjoin each other and two chain warp threads will adjoin, alternating in pairs but differently divided in the grouping 30 for tuft application.

In Figures 32 and 33 the knots are in line along the length of the rug with the same warp thread grouping for application of the knots.

In Figures 34 and 35 the warp thread grouping 35 is the same but the knots of successive rows or courses are right and left respectively.

In Figures 36 and 37 the knots are all right hand knots and the pairing differs in alternate courses of knots, the eyes of the knots surrounding different pairs in one course from the pairs 40 surrounded by the eyes in the next course. In Figures 40 and 41 the warp threads are paired the same for successive courses, but the knots are alternated, rights in one course and lefts in the 45 next.

In Figures 32 and 33 the weft threads alternate, one weft over and one weft under the same warp threads, treating the warp threads in pairs, i. e., 50 one over one pair of adjoining warp threads and the other under the same pair of warp threads between each two courses.

In Figures 34 and 35 the weft threads alternate but alternate in position with the chain warp 55 threads and with pairs of stuffer type warp threads. One goes over a chain warp thread and under the next three warp threads and the other reverses these positions.

In Figures 36 and 37, 38 and 39, the two weft threads are carried through together both over the same warp threads and both under the same warp threads, the warp threads alternating in pairs.

In Figures 40 and 41 any of the knot formations indicated can be used along with any weft 65 formation, the figures being shown to indicate only a different arrangement of the stuffer type warp threads and chain warp threads respectively.

Where two weft threads only are used between 70 two adjoining rows of tufts or knots as in Figures 1 to 8 there are advantages in both forms shown in Figures 1 and 3 and in Figures 5 and 7, respectively. In the earlier of these forms the positions of the warp threads in the sheds are 75

changed so that the weft threads 17 pass over the warp threads under which the weft threads 18 have passed and pass under the warp threads over which the weft threads 18 have passed. This 5 requires shuttle operation. If a needle were used each "shot" would lay two weft threads for each shed position.

In the form of Figures 5 and 7 the two weft threads 17 and 18 are carried both under the 10 same warp threads and both over the same other warp threads. This is well suited to needle insertion.

With nearly the same tuft or knot spacing, the forms of Figures 1 and 3 gives a firmer fabric 15 whereas the forms of Figures 5 and 7 gives a looser fabric, which, when made in a loom, is more nearly comparable with hand work than the other.

The tuft or knot spacing will be a trifle close 20 with the second forms because of the additional shedding operation in the first form and the corresponding more compact beating up in the second form.

The conditions discussed in regard to Figures 25 1 and 3 as compared with Figures 5 and 7 in a three-warp-thread grouping are also present in Figures 32 and 34 as compared with Figures 36 and 38 in a four-warp-thread grouping.

In view of our invention and disclosure variations and modifications to meet individual whim or particular need will doubtless become evident to others skilled in the art, to obtain all or part of the benefits of our invention without copying the structure shown, and we, therefore, claim all 35 such in so far as they fall within the reasonable spirit and scope of our invention.

Having thus described our invention, what we 40 claim as new and desire to secure by Letters Patent is:

40 1. A knotted pile fabric having stuffer type warp threads woven straight through the fabric in unbending relation and chain warp threads which are bent below and above the weft, weft uniting the stuffer and chain warp threads and tuft knots passing back of all of the warp threads and forming a back for them.

45 2. A knotted pile fabric having stuffer type warp threads which are woven straight through the fabric in unbending relation and chain warp threads bent above and below the warp threads, in groupings of one stuffer type warp thread to two chain warp threads, weft uniting the warp threads and Persian knots having their eyes about chain warp threads only and their loops about stuffer type and chain warp threads.

50 3. A knotted pile fabric having stuffer type warp threads woven straight through the fabric in unbending relation and chain warp threads which are bent below and above the weft, in groupings of three, one stuffer type warp thread to two chain warp threads, weft uniting the warp threads and Persian knots having their eyes each about one of the warp threads and their loops about one each of the warp threads and including a stuffer type warp thread within each knot.

55 4. A knotted pile fabric having stuffer type warp threads woven straight through the fabric in unbending relation and chain warp threads which are bent below and above the weft, in groupings of three, one stuffer type warp thread to two chain warp threads, weft holding the warp threads together and Persian knots having their eyes each about one of the warp threads and their loops about the other two of the warp

threads, and covering the stuffer type warp threads at the back.

5 5. A knotted pile fabric having stuffer type warp threads woven straight through the fabric in unbending relation and chain warp threads which are bent below and above the weft, in groupings of three, one stuffer type warp thread to two chain warp threads, weft holding the warp threads together and Persian knots about the warp threads having their eyes each about 10 two warp threads of the group and their loops each about the third of the warp threads, and forming a backing for the stuffer type warp threads.

15 6. A knotted pile fabric having stuffer type warp threads woven straight through the fabric in unbending relation and chain warp threads which are bent below and above the weft, in groupings of three, one stuffer type warp thread to two chain warp threads, weft holding the warp 20 threads together and Persian knots about the warp threads including in each knot a stuffer type warp thread and having right-handed knots in one course and left-handed knots in the next course of knots.

25 7. A knotted pile fabric having stuffer type warp threads woven straight through the fabric in unbending relation and chain warp threads which are bent below and above the weft, in groupings of three, one stuffer type warp thread to two chain warp threads, weft holding the warp threads together and Persian knots about the warp threads having right-handed knots in alternate courses and left-handed knots in intermediate courses and having different groupings 35 of the warp threads within the knots in adjoining courses, but each knot including a stuffer type warp thread.

8. A knotted pile fabric having stuffer type warp threads woven straight through the fabric 40 in unbending relation and chain warp threads, which are bent below and above the weft, in groupings of three, one stuffer type warp thread to two chain warp threads, weft holding the warp threads together and Persian knots about the 45 warp threads having different groupings of the warp threads within the knots for adjoining courses of the knots, but each knot including a stuffer type warp thread.

9. A knotted pile fabric having stuffer type 50 warp threads woven straight through the fabric in unbending relation and chain warp threads, which are bent below and above the weft, weft holding the warp threads together and Persian knots, each knot about stuffer type and chain 55 warp threads having alternating right and left knots differently placed with respect to the grouping of the warp threads in adjoining courses.

10. A knotted pile fabric having stuffer type warp threads woven straight through the fabric 60 in unbending relation and chain warp threads which are bent below and above the weft, in groupings of one stuffer type warp thread to two chain warp threads, weft holding the warp threads together and Persian knots about the 65 warp threads having the eyes and loops, respectively, of each knot, one including two warp threads and the other one warp thread of a group including a stuffer type warp thread in each knot.

70 11. A knotted pile fabric having stuffer type warp threads woven straight through the fabric in unbending relation and chain warp threads which are bent below and above the weft, in groupings of one stuffer type warp thread to two 75

chain warp threads, weft holding the warp threads together and Persian knots about the warp threads having the eyes and loops of the knots including for each knot one two-warp threads and the other one-warp thread of the group and differing in the grouping of the warp threads in adjoining courses of knots.

12. A knotted pile fabric having stuffer type warp threads woven straight through the fabric in unbending relation and chain warp threads which are bent below and above the weft, arranged in groups successively recurring across the fabric, weft holding the warp threads together and knots about the warp threads differing in the number of warp threads included in the knot from the number of warp threads included in the group but each knot including a stuffer type warp thread, the knots forming backing for all of the stuffer type warp threads across a weftwise course of the fabric.

13. In a knotted pile fabric having stuffer type warp threads woven straight through the fabric in unbending relation and chain warp threads which are bent below and above the weft, in a three-warp thread grouping, knots including two warp threads, one of which is a stuffer type warp thread and weft thread between the courses of the fabric.

14. A knotted pile fabric having stuffer type warp threads woven straight through the fabric in unbending relation and chain warp threads which are bent below and above the weft, weft holding the warp threads together and Persian knots having the eyes of the knots surrounding and forming a back coverage for their respective stuffer type warp threads and the loops engaged each with a chain warp thread.

15. A knotted pile fabric having stuffer type warp threads woven straight through the fabric in unbending relation and chain warp threads which are bent below and above the weft, weft holding the warp threads together and Persian knots characterized by the loop of each knot forming coverage for the back of a stuffer type warp a thread and the eye of each knot surrounding a chain warp thread.

16. In a pile fabric, stuffer type warp threads woven straight through the fabric in unbending relation and chain warp threads which are bent below and above the weft, arranged in groups of two chain warp threads to one stuffer type warp thread, rows or courses of Persian knots about warp threads only, including each a stuffer type warp thread and each forming backing for the stuffer type warp thread and for a chain warp thread and weft threads between the courses of knots comprising two weft shots between each two courses of knots, one weft shot under certain warp threads over which the other weft shot passes and over certain warp threads under which the other weft shot passes.

17. A knotted pile fabric having warp threads in groupings including each two classes, one a stuffer type warp thread woven straight through in unbending relation and the other two chain warp threads which are bent below and above the weft, weft holding the warp threads together and Persian knots about these warp threads having the eyes of the knots each about warp threads of one class and having their loops each about warp threads of the other class.

18. A knotted pile fabric having stuffer type warp threads woven straight through the fabric in unbending relation and chain warp threads which are bent below and above the weft, side by side throughout the width of the fabric, weft holding the warp threads together and knots about both stuffer type and chain warp threads including and forming backing for the stuffer type warp threads.

19. A knotted pile fabric having stuffer type warp threads woven straight through the fabric in unbending relation and chain warp threads which are bent below and above the weft, in groupings of three warp threads, weft threads binding the warp threads together and having the knots of the fabric each passing about one stuffer type warp thread and at least one chain warp thread and forming a cover for the back of the stuffer type warp thread of its group.
